US00D994288S

(12) United States Design Patent (10) Patent No.: US D994,288 S
Harper et al. (45) Date of Patent: * Aug. 8, 2023

(54) SHOE

(71) Applicant: NIKE, Inc., Beaverton, OR (US)

(72) Inventors: Asha Harper, Beaverton, OR (US);
Niek Pulles, Portland, OR (US)

(73) Assignee: NIKE, Inc., Beaverton, OR (US)

() Term: 15 Years

(21) Appl. No.: 29/795,220

(22) Filed: Jun. 17, 2021

(51) LOC (14) Cl. 02-04

(52) U.S. Cl.

USPC D2/947

(58) Field of Classification Search

USPC D2/947, 962, 969, 972, 973, 977, 978,

D2/946

CPC .. A43B 5/10; A43B 5/06; A43B 11/00; A43B

13/16; A43B 1/0072; A43B 13/023; A43B

13/127

(57) CLAIM

The ornamental design for a shoe, as shown and described.

DESCRIPTION

FIG. 1 is a front perspective view of a shoe showing our new design;
FIG. 2 is a side view thereof;

FIG. 3 is a rear perspective view thereof;

FIG. 4 is an enlarged view of the claim as shown in FIG. 2 with environment removed for clarity purposes;

FIG. 5 is a front perspective view of a shoe showing an alternate embodiment of our new design;

FIG. 6 is a side view thereof;

FIG. 7 is a rear perspective view thereof; and,

FIG. 8 is an enlarged view of the claim as shown in FIG. 6 with environment removed for clarity purposes.

The broken lines immediately adjacent to the shaded area define the bounds of the claimed design and form no part thereof. The broken lines depicting the remainder of the shoe form no part of the claimed design.

1 Claim, 8 Drawing Sheets
